(57) **CLAIM**

The ornamental design for a power module and alternator rotor lock, as shown and described.

DESCRIPTION

FIG. 1 is a top perspective view of a power module and alternator rotor lock;

FIG. 2 is a bottom perspective view thereof;

FIG. 3 is a front side elevation view thereof;

FIG. 4 is a rear side elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in the figures illustrate portions of the power module and alternator rotor lock that form no part of the claimed design.
